FLOOR PROTECTION FOR RAILWAY CARS

William J. Tangerman, Hammond, Ind., assignor
to Standard Railway Equipment Manufacturing Company, Chicago, Ill., a corporation of
Delaware

Application August 10, 1940, Serial No. 352,046

7 Claims. (Cl. 105—422)

The invention relates to railway freight cars of the house or roofed type and has for its object to provide means for protecting the wooden floors now in general use in such type of equipment, which means will not interfere with the securing of blocking to the wooden flooring.

Another object is to protect the wooden flooring with a metallic sheathing which is perforated so that the car lading may be secured to the flooring through the apertures.

The floors of railway cars are subjected to a great deal of abuse by nails and spikes being driven into them when attaching blocking to them, and also by trucking the lading into the car and by dragging pieces of lading from one part of the car to another. That portion of the car between the opposite side wall doorways is given the most abuse by lading being hauled through the car (by truck or otherwise) to an adjacent car. However, my improved floor protection may be applied over the entire area of the floor if desired.

Another object of the invention is to prevent the curling of the edges of the floor protecting plates. Heavy loads are often hauled into railway cars upon trucks having wheels of small diameter and the pressure of such wheels upon the floor of the car presses the central portions of the protecting plate into the wood floor and causes the edges of the plate to curl upwardly.

Another object is to provide a floor protection which may be easily installed and parts of which may be easily removed and replaced when it is desired to repair the floor.

Other objects and advantages of my invention will be apparent from the following detailed description by referring to the accompanying drawings:

In the drawings:

Fig. 1 is a plan view of the portion of a railway car floor adjacent the doorways of the car.

Fig. 2 is a transverse section through the car at the doorway, as indicated by line 2—2 of Fig. 1.

Fig. 3 is a transverse section through the side wall of the car at a distance removed from the doorway, as indicated by line 3—3 of Fig. 1.

Fig. 4 is a section through the floor of the car, as indicated by line 4—4 of Fig. 1.

Figs. 5, 6 and 7 are enlarged views of the portions of Fig. 4, included within the circles marked 5, 6 and 7 respectively.

Figs. 8 and 9 are views similar to Figs. 5 and 6 respectively showing modified constructions.

As shown in Figs. 2 and 3 the underframe 10 of the car comprises a center sill 11 and side sills

13 spaced therefrom on either side thereof. The side sills 13 are connected to the center sill 11 by cross members, such as bolsters, cross bearers and cross ties not shown in the drawings. Additional support for the floor is provided by the longitudinally extending angle shaped floor supports 14. Longitudinally extending Z-shape auxiliary sill members 16 are secured to the side sills 13 and project upwardly and outwardly therefrom. The auxiliary sill members 16 support the side wall 17 of the car, including the spaced apart door posts 19 shown in plan section in Fig. 1. The doorway is included between the door posts 19. Side plates 20 form the upper edges of the side walls 17 and the roof 22 extends between the side plates 20. The wooden floor 23 comprises boards extending crosswise of the car and resting upon the center sill 11 and side sills 13. The ends of the boards preferably overlie the webs of the auxiliary sill members 16.

The protecting covering 25 for the wooden floor 23 comprises a plurality of metallic sheets 26 which extend substantially between the side walls 17. The metallic sheets 26, preferably of relatively light gauge ($\frac{1}{8}$ " has been found suitable in most cases), are bolted to the wooden floor 23 by bolts 28 having countersunk heads, as shown in detail in Fig. 7. Such bolts 28 may extend through the metallic sheet 26 and the wooden floor 23, as shown in Fig. 7, or may extend, in addition, through parts of the underframe 10, such as through the longitudinal floor supports 14, as shown in Figs. 2 and 3. The protecting covering 25 may cover the entire floor of the car or merely that part of the floor included between the doorways of the car. A preferable construction embodies a protecting covering which extends the width of one sheet beyond the doorposts 19 on either side of the doorway. The threshold plate 29 may overlap the flooring protecting sheets 26, as shown at the left of Fig. 2, or may abut the protecting sheets 26, as shown at the right of Fig. 2.

In the preferred form of the invention shown in Fig. 5, the adjacent edges of each pair of sheets 26 are overlapped. A groove 35 is provided in the wooden floor 23 and the overlapped parts 36 of the sheets 26 are depressed below the general level of the sheets and disposed in the groove 35. The depressed or overlapped parts 36 are connected to the body parts of the sheets 26 by inclined webs 38. A member 39, preferably comprising a strip, overlies the overlapped parts 36 of the sheets 26 and has its edges 41 beveled complementary to the inclined webs 38 of the

sheets 26. The upper surface 42 of the member 39 is preferably flush with the body parts of the sheets 26 and the member 39 is tightly secured to the wooden floor 23 by bolts 44 having countersunk heads. The bolts 44 may extend only through the wooden floor 23, as shown in Fig. 5, or may extend in addition through parts of the underframe 10 of the car.

Fig. 6 shows a section at the extreme edge of the floor protecting covering 25. The edge 49 of the single sheet 50 is depressed in a manner similar to that shown in Fig. 5 and a similar beveled strip 39 overlies the depressed part 49 of the sheet. Bolts 44 as heretofore described extend through the strip 39 and wooden floor 23 and clamp the edge of the sheet 50.

Fig. 9 shows a modified means of securing the floor protecting covering 25 to the wooden floor 23. The sheet 50 is formed with a depending flange 52 which is disposed in a groove 53 in the wooden floor 23. Bolts 54 having countersunk heads secure the sheet 50 to the wooden floor 23.

In the modification shown in Fig. 8, the adjacent edges 55 of the sheets 56 abut rather than overlap. The depressed parts 58 are connected to the body parts of the sheets 56 by inclined webs 59, as heretofore described, and the usual beveled strip 39 overlies the depressed parts 58 of the sheets. In this case, notches are provided in the edges 55 of the sheets 56 to accommodate the bolts 44 in place of the holes provided in the depressed parts of the sheets shown in Fig. 5.

The wood used in the wooden floors of cars of this type is commonly of a relatively soft type. Heavy loads are hauled in on trucks having wheels of small diameter and such wheels squeeze the body part of the sheet into the wooden floor with consequent upcurling of the edges unless such edges are securely clamped. As shown in Fig. 5 particularly, the beveled edges 41 of the strip 39 are in contact with the inclined webs 38 of the sheets 26 over relatively small areas at the upper parts of the web 38. The overlapped parts 36 of the sheets 26 are securely fastened by being clamped between the strip 39 and the wood floor 23. The marginal portion of each sheet 26 is thus fastened at two spaced apart places; i. e., at the webs 38 and the overlapped parts 36. As hereinabove pointed out, the rolling of heavily loaded wheels over the floor tends to curl the edges of the sheets upwardly. Such curling is resisted, in part, by the strip 39 partially overlying the webs 38 and by the contact areas between the strip 39 and webs 38 being positioned substantially at the level of the body parts of the sheets 26. The possibility is thus eliminated that the marginal parts of the sheets 26 might straighten out or otherwise deform and thereby permit curling of the sheets.

It is evident from Fig. 5 that each of the overlapped parts 36 is provided with holes through which the bolts 44 are inserted. When the bolts 44 are tightened, the strip 39 forces the right hand sheet 26 toward the right and the left hand sheet 26 toward the left preferably as far as permitted by the clearance between the bolts 44 and said holes. A tightly interlocked joint is thus formed to resist upcurling of the sheets 26.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car having a wood floor, a protecting covering for said floor comprising a pair of metallic sheets arranged with their adjacent 5 marginal portions overlapping, a relatively shallow groove in said wood floor, said marginal portions being depressed below the general level of said sheets and disposed in said groove, a member overlying said marginal portions and having its upper surface substantially flush with the general level of said sheets, and means arranged to secure said member to said wood floor.
2. In a railway car having a wood floor, a protecting covering for said floor comprising a pair of metallic sheets arranged with their adjacent 15 marginal portions overlapping, a relatively shallow groove in said wood floor, said marginal portions being depressed below the general level of said sheets and disposed in said groove, a member overlying said marginal portions 20 comprising solid metal having a depth extending from the uppermost of said marginal portions substantially to the general level of said sheets and a width extending substantially between the body parts of said sheets, bolts extending through the marginal portions of both of said sheets and arranged to secure said member to said wood floor, and apertures in said sheets for securing a lading to said floor.
3. In a railway car having a wood floor, a protecting covering for said floor comprising a pair of metallic sheets arranged with their adjacent 25 marginal portions overlapping, a groove in said wood floor, said marginal portions being depressed below the general level of said sheets 30 and disposed in said groove, a member overlying said marginal portions and arranged to form a substantially smooth and continuous surface in cooperation with the body parts of said sheets, and securing means arranged to secure said member to said wood floor, said marginal portions being connected to the body parts of said sheets by inclined webs so as to form a downwardly converging depression, and said member 35 having edges complementary with and engaging said webs.
4. In a railway car having a wood floor, a protecting covering for said floor comprising a pair of relatively thin metallic sheets arranged 40 with their marginal portions overlapping, a relatively shallow groove in said wood floor, said marginal portions being depressed below the general level of said sheets and disposed in said groove, a member overlying said marginal portions 45 and having its upper surface substantially flush with the general level of said sheets, said member having a great thickness relative to said sheets to prevent curling of the edges thereof and a small thickness relative to said floor to avoid weakening the floor, and bolts arranged to secure said member to said wood floor.
5. In a railway car having a wood floor, a protecting covering for said floor comprising a pair of metallic sheets arranged with their adjacent 50 marginal portions overlapping, a groove in said wood floor, said marginal portions being depressed below the general level of said sheets and disposed in said groove, a strip overlying said marginal portions, said marginal portions being connected to the body parts of said sheets by downwardly converging webs, said strip having downwardly converging sides, and means to tightly secure said strip to said floor, thereby 55 creating contact pressure between the lower side of the strip and the uppermost of said marginal

portions and between said converging webs and said converging sides.

6. In a railway car having a wood floor, a protecting covering for said floor comprising a pair of metallic sheets arranged with their adjacent marginal portions overlapping, a relatively shallow groove in said floor, said marginal portions being depressed below the general level of said sheets and disposed in said groove, a member overlying said marginal portions and arranged to form a substantially smooth and continuous surface in cooperation with the body parts of said sheets, bolts extending through the marginal portions of both of said sheets and arranged to secure said member to said wood floor, said marginal portions being connected to the body parts of said sheets by downwardly converging webs and said member having down-

wardly converging edges arranged to engage with said webs, and apertures in said sheets for securing a lading to said wood floor.

7. In a railway car having a floor comprising an upper surface consisting of a pair of metallic sheets arranged with their marginal portions overlapping and depressed below the general level of said sheets, a member overlying said marginal portions, said marginal portions being connected to the body parts of said sheets by inclined webs so as to form a downwardly converging depression and said member having edges beveled to engage with said webs, and means to secure said member to the floor so as to create a contact pressure between said member and the marginal portions and webs of the sheets.

WILLIAM J. TANGERMAN.
